ABSTRACT

Isopentene is produced in a high yield by the method wherein a hydrocarbon mixture containing isobutene and n-butene is brought into contact with a catalyst which has been prepared by depositing a molybdenum compound and at least one additional metal compound such as cobalt, tin, silver, zinc, cadmium, lead, bismuth or antimony compound, on an alumina carrier and calcining the compounds, deposited thereon, the contact being carried out in the presence of steam in an amount of 0.1 to 25% based on the volume of the hydrocarbon mixture and calculated in terms of volume under standard conditions of 0°C and 760 mmHg in order to dispropionate the hydrocarbon mixture, and the resultant isopentene is isolated from the reaction mixture.

22 Claims, No Drawings

METHOD FOR PRODUCING ISOPENTENE

The present invention relates to a method for producing isopentene, more particularly, relates to a method for producing isopentene by disproportionation of a hydrocarbon mixture containing isobutene and n-butene.

The term "isopentene" used herein refers to 2-methylbutene-1, 2-methylbutene-2, 3-methylbutene-1 or mixtures of two or more of the above-mentioned compounds.

The term "n-butene" used herein refers to cis-butene-2, trans-butene-2, butene-1 or mixtures of two or more of the above-mentioned butenes.

It is known that olefins may be disproportionated by bringing them into contact with a molybdena-alumina catalyst. However, it is also known that if the conventional disproportionation method using the molybdena-alumina catalyst is applied to olefin mixtures containing mainly hydrocarbons having four carbon atoms, such as isobutene and n-butene, this application involves the following disadvantages.

1. Low disproportionation conversion

The term "disproportionation conversion" used herein refers to the ratio in percent of the weight of the disproportionation product to the original weight of the hydrocarbon mixture subjected to the disproportionation process.

2. Low content of C_5 fraction in the resultant disproportionation product

The term " C_5 fraction" used herein refers to a fraction of distillate consisting essentially of hydrocarbons having five carbon atoms, separated from the disproportionation product.

3. High content of C_{+6} fraction in the disproportionation product

The term " C_{+6} fraction" used herein refers to a fraction of distillate consisting essentially of hydrocarbons having six or more carbon atoms, separated from the disproportionation product.

4. Low content of isopentene in the C_5 fraction

Accordingly, it is known that the conventional method as stated above has a low industrial value for producing isopentene by the disproportionation process. This will become apparent by reading Reference Example 1 illustrated hereinafter.

Further, in the conventional disproportionation of olefin using a conventional catalyst, for example, molybdena-alumina catalyst, it is known that supplying steam to the disproportionation reaction system causes a remarkable decrease of the disproportionation conversion. This will become apparent by reading Reference Example 2 described hereinafter.

An object of the present invention is to provide a method for producing a high yield of isopentene by disproportionation of a hydrocarbon mixture containing isobutene and n-butene such that the hydrocarbon mixture can be disproportionated in a high conversion, the resultant disproportionation product contains a high content of C_5 fraction and the C_5 fraction contains a very high content of isopentene.

The above object can be accomplished by the method of the present invention which comprises the steps of bringing a hydrocarbon mixture containing isobutene and n-butene into contact with a catalyst which has been prepared by depositing a molybdenum compound and at least one additional metal compound se-

lected from the group consisting of cobalt, tin, silver, zinc, cadmium, lead, bismuth and antimony compounds on an alumina carrier and calcining the compounds deposited thereon, the contact being carried out in the presence of steam in an amount of 0.1 to 25% based on the volume of said hydrocarbon mixture and calculated in terms of volume under standard conditions of a temperature of 0°C and a pressure of 760 mmHg, at a temperature of 220° to 380°C, and isolating the resultant isopentene from the reaction mixture.

In the method of the present invention, the disproportionation product consists of a relatively high content of propylene, a relatively high content of C_5 fraction and a relatively low content of C_{+6} fraction which fractions consist of olefin compounds. That is, the disproportionation product obtained by the method of the present invention contains a high content of propylene and the C_5 fraction both of which are very valuable to the chemical industry.

20 The disproportionation step in the method of the present invention may result in dimerization and isomerization of a minor portion of the hydrocarbon mixture while the major portion of the hydrocarbon mixture is disproportionated.

25 The catalysts usable for the method of the present invention are prepared by depositing a molybdenum compound and at least one additional metal compound selected from the group consisting of cobalt, tin, silver, zinc, cadmium, lead, bismuth and antimony compounds on an alumina carrier and calcining the compounds deposited on the alumina carrier.

30 The additional metal compounds may be halides, sulfates, nitrates, carbonates, hydroxides, oxides, hydroxycarbonates and organic acid salts of cobalt, tin, silver, zinc, cadmium, lead, bismuth and antimony. The cobalt compound may be cobalt chloride, cobalt nitrate, cobalt sulfate, cobalt acetate, cobalt formate, cobalt oxalate, cobalt hydroxide, cobalt carbonate or cobalt oxide.

35 40 The tin compound may be tin (II) chloride (stannous chloride), tin (II) bromide, tin (II) oxide, tin (II) nitrate or tin (II) acetate.

45 The silver compound usable for the catalyst may be silver chloride, silver bromide, silver nitrate, silver carbonate, silver oxalate, silver oxide or silver hydroxide.

The zinc compound usable for the catalyst may be zinc chloride, zinc bromide, zinc sulfate, zinc nitrate, zinc carbonate, zinc oxalate, zinc acetate or zinc oxide.

50 The cadmium compound usable for the catalyst may be cadmium chloride, cadmium nitrate, cadmium sulfate, cadmium carbonate, cadmium oxide, cadmium acetate or cadmium oxalate.

The lead compound usable for the catalyst may be lead chloride, lead nitrate, lead sulfate, lead carbonate, lead hydroxide, lead hydroxycarbonate, lead oxide, lead acetate or lead formate.

55 The bismuth compound usable for the catalyst may be bismuth chloride, bismuth nitrate, bismuth sulfate, bismuth hydroxycarbonate, bismuth oxide or bismuth oxalate.

The antimony compound usable for the catalyst may be antimony chloride, antimony sulfate, antimony hydroxide, or antimony oxide.

60 65 The molybdenum compound usable for the preparation of the catalyst for the method of the present invention may be selected from the molybdenum compounds usable for the ordinary catalyst for the conventional

method, preferably, may be molybdenum oxide, ammonium molybdate, molybdenum chloride or molybdenum oxide chloride.

The alumina usable as a carrier for the preparation of the catalyst for the method of the present invention may be preferably selected from activated alumina, for example, γ -alumina and η -alumina. Such alumina may have the usual configuration of the conventional catalysts.

Preferably, the alumina usable for the catalyst of the method of the present invention is fine particles of a 2 to 100 mesh size, more preferably, 4 to 50 mesh size.

The molybdenum compound and the additional metal compound as specified above may be deposited on the alumina carrier by conventional methods, for example, the co-precipitation method wherein all of the molybdenum compound, the additional metal compound and an aluminium compound are simultaneously precipitated from the solution thereof, or the impregnation method wherein the alumina is impregnated with a solution of both the compounds and is then dried.

In the impregnation method, the molybdenum compound and the additional metal compound may be deposited simultaneously on the alumina or separately deposited in any order. For example, the molybdenum compound is deposited on the alumina and calcined to remove water absorbed by the alumina, and thereafter, one or more of the additional metal compounds are deposited on the molybdenum compound-deposited alumina, and calcined to prepare the desired catalyst. Also, the additional metal compound may be deposited on a commercial molybdenum-alumina catalyst. The molybdenum compound and the additional metal compound deposited on the alumina carrier are calcined at a temperature of 300° to 1000°C, preferably, 500° to 700°C for 3 to 10 hours in air flow or nitrogen flow, by a conventional calcining method, for example, using an electric furnace.

The catalyst usable for the method of the present invention preferably contains 5 to 20% of the calcined molybdenum compound and 0.5 to 10%, more preferably, 1 to 5%, of the additional metal compounds each based on the weight of the alumina and each calculated in terms of oxide corresponding to the compound.

The hydrocarbon mixture usable for the method of the present invention contains isobutene and n-butene. It is preferable that isobutene in the hydrocarbon mixture be in an amount of 30% or more, more preferably, 30 to 60% by weight. That is, the n-butene may contain butene-1. In the conventional disproportionation method for butenes, it is known that an increase in the butene-1 content in the hydrocarbon mixture causes an undesirable increase in the content of n-pentene in the C_5 fraction. However, in the disproportionation step of the method of the present invention, butene-1 in the hydrocarbon mixture is isomerized to butene-2 and simultaneously disproportionated. Accordingly, in the method of the present invention, the undesirable production of n-pentene is very little. That is, the C_5 fraction produced by the process of the present invention includes a very high content of isopentene; in other words, it consists essentially of isopentene.

The hydrocarbon mixture usable for the method of the present invention may contain, other than isobutene and n-butene, hydrocarbons such as n-butane, isobutane, propylene, propane, 1,3-butadiene, isopen-

tane, isopentene, isoprene, n-pentane and n-pentenes. It is preferable that the total content of the other hydrocarbons contained in the hydrocarbon mixture be not higher than 15% by weight. Especially, it is desirable for the content of conjugated diene compounds, for example, 1,3-butadiene and isoprene, to be 1.0% by weight or less.

The hydrocarbon mixture usable for the method of the present invention may be a so-called spent BB fraction 10 which is an extraction residue prepared by extracting 1,3-butadiene from a fraction of distillate consisting of hydrocarbons having four carbon atoms (C_4 fraction) produced by thermal decomposition or catalytic cracking of natural gas, petroleum gas, naphtha or 15 other petroleum fraction.

In the disproportionation step in the method of the present invention, there is no limitation in feed rate of the hydrocarbon mixture. However, it is preferable that the hydrocarbon mixture be brought into contact with 20 the catalyst at a flow rate, per 1 cm³ of the catalyst, of 50 to 2,000 cm³/hour, more preferably, 100 to 1,000 cm³/hour calculated in terms of volume under the standard conditions of a temperature of 0°C and a pressure of 760 mmHg.

25 In the method of the present invention, steam is fed into the disproportionation process in an amount of 0.1 to 25%, preferably, 0.2 to 10.0% based on the volume of the hydrocarbon mixture to be disproportionated and calculated in terms of volume under standard conditions. If the feed of steam is less than 0.1% by volume, undesirable side reactions, such as dimerization of isobutylene, are enhanced. As a result of the enhancement of the undesirable side reactions, the content of C_{+6} fraction in the disproportionation product undesirably increases and the content of isopentene in the C_5 fraction decreases. If the feed of steam is greater than 25% by volume, the disproportionation conversion ratio undesirably tends to be lowered.

30 The steam supply method for the disproportionation process may be optionally selected from conventional methods if the method can feed steam at a uniform and stable rate. For example, in one steam supply method, the hydrocarbon mixture flows through a water bath maintained at a predetermined temperature so that a quantity of water is vaporized and mixed with the hydrocarbon mixture at a constant rate. In an another steam supply method, the hydrocarbon mixture is admixed with a predetermined amount of steam which has been preliminarily generated. In still another steam supply method, the hydrocarbon mixture flows along the surface of a water bath having a predetermined temperature so as to mix with steam vaporized from the water bath. The hydrocarbon mixture containing the predetermined amount of steam is brought into contact with the catalyst.

35 In still another steam supply method, the hydrocarbon mixture is introduced into an aqueous solution saturated with a metal salt which is effective to maintain the vapor pressure of the solution constant, for example, calcium chloride, potassium bromide, zinc sulfate and magnesium nitrate. The mixture is then brought into contact with the catalyst.

40 If it is necessary, the catalyst for the method of the present invention may be treated with an inert gas, for example, nitrogen gas, containing 0.1 to 25% by volume of steam calculated in terms of volume under standard conditions, at a temperature of 100° to 300°C.

This treatment is effective for enhancing initial activity of the catalyst and its effect can be seen in Example 2, illustrated hereinafter.

In the method of the present invention, the disproportionation process is carried out at a temperature between 220° and 380°C, preferably, between 230° and 350°C. A disproportionation temperature of less than 220°C results in an undesirably high content of C₄ fraction in the disproportionation product. Also, a disproportionation temperature of more than 380°C causes a undesirably low ratio of the disproportionation conversion, shortened life of the catalyst and increased decomposition of the hydrocarbon mixture.

Accordingly, the temperatures less than 220°C or more than 380°C are unsuitable for the practical disproportionation process in the method of the present invention.

Disproportionation in the method of the present invention is preferably carried out under normal pressure or a pressurized condition up to 10 kg/cm²G.

When the hydrocarbon mixture containing isobutene and n-butene is disproportionated by the method of the present invention, the resultant disproportionation product consists essentially of propylene, hydrocarbons having five carbon atoms (C₅ fraction) and hydrocarbons having six or more carbon atoms (C₆ fraction). Both the C₅ fraction and C₆ fraction consist of olefins. The content of the C₆ fraction in the disproportionation product does not exceed 25% by weight. The C₅ fraction contains an isopentene content of not less than 95%. Accordingly, the method of the present invention produces high yields of propylene and isopentene which are very useful to the chemical industry. Further, isopentene obtained by the method of the present invention can be readily isolated and purified by conventional methods. That is, the C₅ fraction can be isolated from the reaction mixture by distillation at a temperature of 20° to 40°C under normal pressure. The C₅ fraction thus isolated consists essentially of isopentene and, therefore, can be subjected to an isoprene producing process wherein the isopentene is dehydrogenated.

The present invention will be further illustrated by the following examples which are given for purposes of illustration only and not as limitations to the scope of the present invention.

In the following examples, reference examples and comparison examples, composition of the disproportionation product was determined by the method detailed below. After the disproportionation process was completed, the reaction mixture was subjected to gas chromatography analysis to determine and record amounts of the component hydrocarbons in the reaction mixture. From the record of the gas chromatography analysis which contains the analysis results of all the component compounds in the reaction mixture, the analysis results of the disproportionation product hydrocarbons were isolated from the analysis results of the non-reacted hydrocarbons in the reaction mixture.

From said isolated analysis results, the contents of the component hydrocarbons in the disproportionation product were calculated in %, based on the weight of the disproportional product. Also, the contents of the C₅ fraction and the C₆ fraction were calculated from the result of the gas chromatography analysis in the same manner as stated above. Further, the content of isopentene was calculated on the basis of the weight of the C₅ fraction. The disproportionation conversion

ratio was calculated as a ratio in percent of the weight of the disproportionation product to the original weight of the hydrocarbon mixture subjected to the disproportionation process.

REFERENCE EXAMPLE 1

Production of isopentene using a catalyst composed of a molybdenum compound deposited on an alumina carrier

10 In order to prepare a catalyst, γ -alumina having a 14 to 32 mesh size (ASTM) was impregnated with an aqueous solution of 5% by weight of ammonium molybdate, dried and, then, calcined in air flow at a temperature of 400°C for 4 hours. The resultant catalyst was composed of 92.5% by weight of alumina and 7.5% by weight of the calcined molybdenum compound calculated in terms of molybdenum oxide.

15 A spent BB fraction gas consisting of 48.7% by weight of isobutene, 16.4% by weight of butene-2, 26.3% by weight of butene-1, 1.2% by weight of isobutane, 7.1% by weight of n-butane, and 0.3% by weight of the sum of propane, propylene, 1,3-butadiene and propadiene, was brought into contact with 6 cm³ of the above-prepared catalyst at a flow rate of 500 cm³/cm³.catalyst/hr at a temperature of 250°C under normal pressure to effect the disproportionation of the spent BB fraction.

20 Table 1 indicates the disproportionation conversion ratio in the above process, content of the resultant isopentene in C₅ fraction and composition of the disproportionation product, at the stages 1.5 and 2.5 hours after the start of the disproportionation process.

REFERENCE EXAMPLE 2

Production of isopentene in the presence of steam using the same catalyst as in Reference Example 1

25 The same operation as in Reference Example 1 were repeated except that the same spent BB fraction gas as used in Reference Example 1 was flowed through a water bath maintained at a temperature of 0°C by cooling under normal pressure so that 0.6% by volume of water calculated in terms of volume under standard conditions, i.e., 0°C and 760 mmHg, was mixed with the spent BB fraction gas.

30 Table 1 indicates the results of the above disproportionation process, disproportionation conversion, content of the resultant isopentene in C₅ fraction and composition of the disproportionation product, at the stages of 1.5 and 2.5 hours after the start of the disproportionation process.

Table 1

Ref. Ex. No.	Dispro- portion- ation time (hr)	Dispro- portion- ation con- ver- sion (%)	Content of isopentene in C ₅ fraction (%)	Composition of disproportionation product (%)		
				Pro- pylene	C ₅ frac- tion	C ₆ frac- tion
1	1.5	23.8	65.0	34.4	38.1	25.9
	2.5	16.8	59.0	28.3	40.1	30.2
2	1.5	13.6	94.2	25.4	44.9	26.7
	2.5	12.8	96.2	28.3	45.3	25.9

Note:

The disproportionation products of Reference Examples 1 and 2 included a small amount of ethylene.

C₅: Mixture of hydrocarbon each having five carbon atoms.

C₆: Mixture of hydrocarbons each having six or more carbon atoms.

From Table 1, it is obvious that in the molybdenum-alumina catalyst system, the utilization of steam results in a decrease of the disproportionation conversion whereas the content of the C₅ fraction in the disproportionation product and the content of isopentene in the C₅ fraction increase.

EXAMPLE 1

In order to prepare a catalyst, γ -alumina having a 14 to 32 mesh size was impregnated with an aqueous solution of 5% by weight of ammonium molybdate, dried and calcined at a temperature of 400°C for 4 hours in air flow. The material impregnated and calcined above was impregnated with an aqueous solution of 4.3% by weight of cobalt nitrate, dried and calcined at a temperature of 600°C for 4 hours in air flow. Thereafter, the resultant material was further impregnated with an aqueous solution of 0.7% by weight of tin (II) chloride, dried and, then, calcined at a temperature of 600°C for 3.5 hours in air flow. The resultant catalyst was composed of 92.5 parts by weight of alumina, 1 part by weight of the calcined tin compound calculated in terms of tin oxide (SnO), 2 parts by weight of the calcined cobalt compound calculated in terms of cobalt oxide (CoO) and 7.5 parts by weight of the calcined molybdenum compound calculated in terms of molybdenum oxide (MoO₃).

The same spent BB fraction gas as used in Reference Example 1 was flowed through a water bath maintained at a temperature of 0°C by cooling under normal pressure so as to be mixed with 0.6% by volume of steam calculated in terms of volume under standard conditions, and brought into contact with 6 cm³ of the above-prepared catalyst at a temperature of 250°C under normal pressure in order to effect the disproportionation of the spent BB fraction. The fraction was fed at a flow rate of 500 cm³/cm³.catalyst/hour calculated in terms of volume under standard conditions i.e. 0°C and 760 mmHg. Table 2 indicates the results of the above disproportionation, that is, the disproportionation conversion content of isopentene in C₅ fraction and composition of the resultant disproportionation product at the stages of 1.5, 2.5, 3.5 and 4.5 hours after the start of the disproportionation process.

Table 2

Disproportionation time (hr)	Disproportionation conversion (%)	Content of isopentene in C ₅ fraction (%)	Composition of disproportionation product (%)		
			Propylene	C ₅ fraction	C ₆ fraction
1.5	26.5	100	32.7	49.3	18.0
2.5	24.5	100	34.1	52.6	13.3
3.5	22.4	100	33.5	53.1	13.3
4.5	22.2	100	32.9	55.0	12.1

In comparing Table 2 with Table 1, it is obvious that the process of the present example is superior to that

of Reference Examples 1 and 2 in the disproportionation conversion ratio, the content of C₅ fraction in the disproportionation product and the content of isopentene in the C₅ fraction. Especially, it should be noted that in comparing the present example with Reference Example 2, the use of cobalt and tin compounds as the component of the catalyst is effective for enhancing the disproportionation conversion, the content of the C₅ fraction in the disproportionation product and the content of isopentene in the C₅ fraction.

COMPARISON EXAMPLE 1

The same operations as in Example 1 were repeated except that the spent BB fraction gas was brought directly into contact with the catalyst without it flowing through the water bath. The results are indicated in Table 3.

Table 3

Disproportionation time (hr)	Disproportionation conversion (%)	Content of isopentene in C ₅ fraction (%)	Composition of disproportionation product (%)		
			Propylene	C ₅ fraction	C ₆ fraction
1.5	14.3	90.5	25.9	47.6	26.3
2.5	13.2	94.6	34.2	44.0	21.7

Note: The disproportionation product contained a small amount of ethylene.

From a comparison of Table 3 with Table 2, it is evident that the absence of steam in the disproportionation process results in decreases of the disproportionation conversion, the content of the C₅ fraction in the disproportionation product and the content of isopentene in the C₅ fraction.

EXAMPLES 2, 3, AND 4 AND COMPARISON EXAMPLE 2

In Example 2, the same operations as in Example 1 were repeated except that the same catalyst as in Example 1 was steam-treated by bringing a mixture gas of nitrogen and 0.6% of steam, based on the volume of the nitrogen and calculated in terms of a volume under standard conditions into contact with the catalyst at a flow rate of 1,000 cm³/cm³.catalyst/hr at a temperature of 250°C for 30 minutes. The results are indicated in Table 4.

In Example 3, the same procedures as in Example 1 were repeated except that the disproportionation process was carried out at a temperature of 300°C instead of 250°C. The results are indicated in Table 4.

In Comparison example 2, the same procedures as in Example 1 were repeated except that the disproportionation temperature was 200°C instead of 250°C. The results are indicated in Table 4.

In Example 4, the same procedures as in Example 1 were repeated except that the feed rate of the same spent BB fraction gas as in Example 1 was 1,000 cm³/cm³.catalyst/hr calculated in term of volume under standard condition, i.e. 0°C and 760 mmHg. The results are shown in Table 4.

Table 4

Example No.	Feed rate of material hydrocarbon mixture (cm ³ /cm ³ catalyst/hr)	Disproportionation temperature (°C)	Disproportionation time (hr)	Disproportionation conversion (%)	Content of isopentene in C ₅ fraction (%)	Composition of disproportionation product (%)

Example 2	500	200	1.5	12.1	100	36.0	50.9	13.1
Example 4	1000	250	3.5	14.2	100	30.7	54.8	14.5

EXAMPLES 5 THROUGH 10

In each of Examples 5 through 10, a catalyst of the composition as indicated in Table 5 was prepared using the same method as used in Example 1. The amount each of the calcined metal compounds in the catalysts was calculated in terms of a metal oxide corresponding to the metal compound. The same procedures as in Example 1 were repeated using the above-prepared catalysts. The results of the disproportionation process in each of the examples at a stage of 3.5 hours after the start of the process, are indicated in Table 5.

15 prepared by the method wherein γ -alumina having 14 to 32 mesh size was impregnated with an aqueous solution of ammonium molybdate, dried and calcined at a temperature of 400°C for 4 hours in air flow. Thereafter, the γ -alumina impregnated and calcined above was further impregnated with an aqueous solution of silver nitrate, dried and, then, calcined at a temperature of 600°C for 3.5 hours in air flow. The same procedures as in Example 1 were repeated four times using the above-prepared catalysts. The disproportionations in the examples were carried out for 3.5 hours. The results are indicated in Table 6.

rectly brought into contact with the catalyst without flowing through the cold water at a temperature of 0°C. At a stage of 3.5 hours after the start of the disproportionation process, the disproportionation conversion ratio was 10.3%, the content of isopentene in C₅ fraction 68.8%, and the disproportionation product contained 29.8% of propylene, 32.2% of C₅ fraction, 34.3% of C₆ fraction and 3.7% of ethylene.

EXAMPLES 11 THROUGH 14 AND COMPARISON EXAMPLE 4

In Examples 11 through 14, four types of catalysts having the compositions as indicated in Table 6 were

60 From Table 6, it is clear that the absence of steam in the disproportionation process results in a considerable decrease of the disproportionation conversion, the content of isopentene in the C₅ fraction and the content of the C₅ fraction in the disproportionation product.

EXAMPLES 15 AND 16

In Example 15, the same operations as in Example 12 were repeated except that the catalyst was prepared by using zinc nitrate instead of silver nitrate.

65 In Example 16, the same operations as in Example 6 were carried out except that the catalyst was prepared by using zinc nitrate in place of tin (II) chloride.

The results of both examples 15 and 16 are indicated in Table 7.

was prepared by the method wherein γ -alumina of 14 to 32 mesh size was impregnated with an aqueous solu-

Table 7

Ex. No.	Catalyst	Disproportionation time (hr)	Disproportionation conversion (%)	Content of isopentene in C_5 fraction (%)	Composition of disproportionation product (%)		
					Propylene	C_5 fraction	C_{+6} fraction
15	Zn-Mo-Al ₂ O ₃	1.5	19.8	100	28.3	47.3	24.4
		2.5	17.1	100	29.9	48.8	21.3
		1.5	25.5	95.2	32.7	51.4	15.9
16	Zn-Co-Mo-Al ₂ O ₃	2.5	25.5	99.8	34.3	52.4	13.3
		3.5	23.1	100	32.2	55.3	12.5
		4.5	22.7	100	31.6	55.2	13.2

COMPARISON EXAMPLE 5

The same operations as in Example 15 were carried out in the absence of steam. At a moment of 3.5 hours after the start of the disproportionation process, the disproportionation conversion was 11.4%, the content of isopentene in C_5 fraction was 66.3% and the disproportionation product contained 24.4% of propylene, 42.0% of C_5 fraction and 32.2% of C_{+6} fraction.

EXAMPLES 17 THROUGH 19

The same procedures as in Example 1 were repeated three times except that the water bath through which the spent BB fraction gas flowed, had the temperatures as shown in Table 8 and after being flowed through the water bath, the spent BB fraction gas included steam in amounts as shown in Table 8. The results are summarized in Table 8.

tion of 5% by weight of ammonium molybdate, dried and calcined at a temperature of 400°C for 4 hours in air flow. Thereafter, the alumina impregnated and calcined above was further impregnated with an aqueous solution of 0.8% by weight of cadmium chloride, dried and, then, calcined at a temperature of 600°C for 3.5 hours in air flow. The resulting catalyst was composed of 1 part by weight of the calcined cadmium compound, 7.5 parts by weight of the calcined molybdenum compound and 92.5 parts by weight of alumina, each calculated in terms of oxide corresponding to the compound.

In Example 20, the same procedures as in Example 1 were carried out using the above-prepared catalyst.

In Comparison Example 6, the same procedures as in Example 20 were carried out except that the spent BB fraction gas was brought directly into contact with the catalyst without flowing it through the water bath and

Table 8

Ex. No.	Temperature of water bath (°C)	Content of steam in material hydrocarbon mixture (% by volume)	Disproportionation time (hr)	Disproportionation conversion (%)	Content of isopentene in C_5 fraction (%)	Composition of disproportionation product (%)		
						Propylene	C_5 fraction	C_{+6} fraction
17	25	3.1	2.5	22.4	100	30.3	53.6	16.4
			3.5	21.1	100	31.6	54.7	13.7
18	40	7.3	2.5	24.1	100	31.2	52.7	16.1
			3.5	22.7	100	32.0	53.9	14.1
19	60	19.7	1.5	20.4	100	29.2	54.9	15.9
			2.5	18.6	100	34.0	51.8	14.2
			3.5	17.8	100	32.3	53.8	13.9

EXAMPLE 20 AND COMPARISON EXAMPLE 6

In Example 20 and Comparison Example 6, a catalyst

the disproportionation was carried out in the absence of steam.

The results are indicated in Table 9.

Table 9

Example No.	Disproportionation time (hr)	Disproportionation conversion (%)	Content of isopentene in C_5 fraction (%)	Composition of disproportionation product (%)		
				Propylene	C_5 fraction	C_{+6} fraction
20	2.5	21.0	100	32.7	49.5	17.8
	3.5	20.0	100	35.9	50.1	14.0
	4.5	17.5	100	36.6	47.5	15.9
Comparison Example 6	2.5	19.0	62.1	33.2	40.6	24.6
	3.5	16.1	60.9	30.2	42.7	25.9
	4.5	12.8	64.0	28.8	43.9	26.1

Note: The disproportionation product of Comparison Example 6 included a small amount of ethylene.

EXAMPLES 21 THROUGH 23

The same operations as in Example 20 were repeated three times except that the catalysts were prepared using, instead of cadmium chloride, lead nitrate (Example 21), bismuth trichloride (Example 22) and antimony trichloride (Example 23).

The results are summarized in Table 10.

EXAMPLES 26 AND 27

The same operations as in Example 20 were repeated twice except that the spent BB fraction gas was fed into the water bath at flow rates of 300 $\text{cm}^3/\text{cm}^3 \cdot \text{catalyst/hr}$ (Example 26) and 1,000 $\text{cm}^3/\text{cm}^3 \cdot \text{catalyst/hr}$ (Example 27) calculated in terms of volume under the standard

Table 10

Ex. No.	Metal Compound	Disproportion- ation time (hr)	Disproportion- ation conversion (%)	Content of isopentene in C_5 fraction (%)	Composition of disproportionation product (%)		
					Propylene	C_5 fraction	C_{+6} fraction
21	Lead nitrate	1.5	12.2	100	28.6	50.9	20.5
		2.5	10.8	100	30.5	51.3	18.2
		3.5	10.8	100	31.0	52.0	17.0
22	Bismuth trichloride	1.5	18.4	96.1	31.8	43.7	24.5
		2.5	16.9	100	36.4	46.4	17.2
		3.5	15.7	100	35.4	48.1	16.5
23	Antimony trichloride	1.5	16.0	100	29.1	44.8	26.1
		2.5	13.8	100	29.9	49.0	21.1
		3.5	13.3	100	33.9	46.0	20.1

COMPARISON EXAMPLE 7

The same procedures as in Example 22 were repeated except that no water bath was used to supply steam to the disproportionation system. The results are indicated in Table 11.

Table 11

Disproportion- ation time (hr)	Disproportion- ation conversion (%)	Content of isopentene in C_5 fraction (%)	Composition of disproportionation product (%)		
			Propylene	C_5 fraction	C_{+6} fraction
1.5	21.8	67.4	28.5	42.1	28.3
2.5	16.9	64.6	27.1	40.7	32.2
3.5	14.2	65.5	23.7	42.7	32.9

Note:

The product of disproportionation included a small amount of ethylene.

EXAMPLES 24 AND 25 AND COMPARISON EXAMPLE 8

In Examples 24 and 25, the same procedures as in Example 20 were repeated twice except that the disproportionation process was carried out at temperatures of 300°C (Example 24) and 350°C (Example 25) in place of 250°C, for 2.5 hours.

In Comparison Example 8, the same procedures as in Example 24 were carried out except that the disproportionation temperature was 200°C.

The results are summarized in Table 12.

55

Table 12

Example No.	Disproportion- ation temperature (°C)	Disproportion- ation conversion (%)	Content of isopentene in C_5 fraction (%)	Composition of disproportionation product (%)		
				Propylene	C_5 fraction	C_{+6} fraction
24	300	19.6	98.5	33.5	53.6	12.9
25	350	12.9	100	28.8	58.9	12.5
Comparison Example 8	200	25.8	85.7	16.3	25.9	57.8

Table 13

Ex. No.	Flow rate ($\text{cm}^3/\text{cm}^3 \cdot \text{catalyst/hr}$)	Disproportion- ation conversion (%)	Content of isopentene in C_5 fraction (%)	Composition of disproportionation product (%)		
				Propylene	C_5 fraction	C_{+6} fraction
26	300	22.5	96.3	29.8	49.8	20.4
27	1,000	11.6	98.7	29.1	51.5	19.4

EXAMPLES 28 AND 29

The same procedures as in Example 20 were repeated twice except that the temperatures of the water baths to which the spent BB fraction gas to be disproportionated was introduced, were 25°C (Example 28) and 60°C (Example 29), and that after it was passed through the water baths, the spent BB fraction gas contained steam in amounts of 3.1% (Example 28) and 19.7% (Example 29) based on the volume of the spent BB fraction gas fed to the disproportionation process. The disproportionation process in both the examples was carried out for 2.5 hours.

The results are indicated in Table 14.

Ex. No.	Temper- ature of water bath (°C)	Content of steam (% by volume)	Dispro- portion- ation conver- sion (%)	Content of iso- pentene in C ₅ frac- tion (%)	Composition of disproportionation product (%)		
					Pro- pylene	C ₅ frac- tion	C ₆₊ frac- tion
28	25	3.1	18.5	100	30.1	50.5	19.4
29	60	19.7	18.0	100	31.5	51.2	17.3

EXAMPLES 30 THROUGH 37

The same operations as in Example 1 were repeated 15 eight times except that a catalyst which has been prepared in a similar manner to that in Example 1, was composed of 86.5 parts by weight of alumina, 1 part by weight of the calcined tin compound calculated in terms of tin oxide (SnO), 3.5 parts by weight of the calcined cobalt compound calculated in terms of cobalt oxide (CoO) and 10 parts by weight of the calcined molybdenum compound calculated in terms of molybdenum oxide (MoO₃), and that the disproportionation processes were carried out at the temperatures under 20 the pressures indicated in Table 15.

The results are indicated in Table 15.

Table 15

Example No.	Disproportionation process		Dispro- portion- ation conversion (%)	Content of isopentene in C ₅ frac- tion (%)	Composition of disproportionation product (%)		
	Pressure (kg/cm ² G)	Temperature (°C)			Propylene	C ₅ frac- tion	C ₆₊ frac- tion
30	2	250	28.6	100	33.6	48.6	17.8
31	2	275	27.7	100	34.7	49.8	15.5
32	2	300	24.7	100	34.8	49.0	16.2
33	3	250	30.7	100	30.9	47.9	21.2
34	3	275	28.9	100	32.2	47.4	20.4
35	3	300	24.2	100	33.1	48.3	18.6
36	4	250	33.8	100	32.8	47.1	20.1
37	5	250	36.9	100	26.8	48.5	24.7

What we claim is:

1. A method for producing isopentene comprising the steps of:
    - bringing a hydrocarbon mixture containing isobutene and n-butene into contact, at a temperature of 220°C to 380°C, with a catalyst which has been prepared by depositing a molybdenum compound and at least one additional metal compound selected from the group consisting of cobalt, tin, silver, zinc, cadmium, lead, bismuth and antimony compounds on an alumina carrier and calcining the compounds deposited, thereon the contact being carried out in the presence of steam in an amount of 0.1 to 25% based on the volume of said hydrocarbon mixture and calculated in terms of volume under standard conditions of a temperature of 0°C and a pressure of 760 mmHg;
    - isolating the resultant isopentene from the reaction mixture.
  2. A method as claimed in claim 1, wherein said hydrocarbon mixture contains more than 30% by weight of isobutene.
  3. A method as claimed in claim 2, wherein said content of isobutene in said hydrocarbon mixture is between 30 and 60% by weight.
  4. A method as claimed in claim 1, wherein said cata-
- lyst contains 5 to 20% of said calcined molybdenum compound and 0.5 to 10% of said calcined additional metal compound based on the weight of said alumina carrier and calculated in terms of oxides corresponding thereto.
5. A method as claimed in claim 4, wherein the content of said calcined additional metal compound is 1 to 5% based on the weight of said alumina carrier and calculated in terms of the oxide corresponding thereto.
  6. A method as claimed in claim 1, wherein said additional metal compound is selected from the group consisting of halides, sulfates, nitrates, carbonates, hydroxides, oxides, hydroxycarbonates and organic acid salts of cobalt, tin, silver, zinc, cadmium, lead, bismuth and antimony.

16. A method as claimed in claim 1, wherein said hydrocarbon mixture is brought into contact with said catalyst at a flow rate of 50 to 2000 cm³/hr, calculated in terms of volume under standard conditions, per 1 cm³ of said catalyst.

17. A method as claimed in claim 16, wherein said flow rate of said hydrocarbon mixture is 100 to 1000 cm³/cm³ catalyst/hr.

18. A method as claimed in claim 1, wherein said steam is fed at a feed rate of 0.2 to 10% based on the volume of said hydrocarbon mixture and calculated in terms of volume under standard conditions.

19. A method as claimed in claim 1, wherein said catalyst is treated with an inert gas containing 0.1 to 25%

by volume of steam calculated in terms of volume under standard conditions, at a temperature of 100 to 300°C.

20. A method as claimed in claim 1, wherein the contact temperature of said hydrocarbon mixture with said catalyst is 230° to 350°C.

21. A method as claimed in claim 1, wherein said isolation of said resultant isopentene is carried out by distillation at a temperature of 20° to 40°C.

22. A method as claimed in claim 1, wherein said disproportionation step is carried out under normal pressure or under a pressurized condition up to 10 Kg/cm²G.
